UNITED STATES PATENT OFFICE.

SHEROD P. BARKSDALE, OF PHILADELPHIA, PENNSYLVANIA.

STEP.

1,386,718.

Specification of Letters Patent. Patented Apr. 13, 1920.

Application filed March 17, 1919. Serial No. 283,123.

To all whom it may concern:

Be it known that I, SHEROD P. BARKSDALE, a citizen of the United States, residing at Philadelphia, in the county of Philadelphia and State of Pennsylvania, have invented certain new and useful Improvements in Steps, of which the following is a specification.

This invention relates to new and useful 10 improvements in door stoops or steps, and the primary object is the provision of a stoop or step of this character that is formed of a plurality of superposed sections, detachably connected, that may be easily assembled or knocked down; any of the sections being adapted to be quickly replaced in case of injury thereto.

Another object of the invention, is to provide a stoop or step of this character that 20 has the sections formed of plastic blocks of the hereinafter described novel construction; permitting the sections to be very economically manufactured, and materially reducing the cost of construction of a structural element of this type.

A further object of the invention is to provide a plastic stoop or step of this character, which is easily and simply constructed, and inasmuch as the various sections are durable 30 and portable, they may be made stock articles, and can be assembled without the use of skilled labor, or the employment of the ordinary forms.

With these and numerous other objects in 35 view, my invention consists of the novel features of construction, combination, and arrangement of parts, which will be herein referred to and more particularly pointed out in the specification and claims.

40 In the accompanying drawings:

Figure 1, is a perspective view of the door stoop or step.

Fig. 2, is a transverse vertical sectional view.

45 Fig. 3, is a longitudinal vertical sectional view taken through the upper section.

Fig. 4, is a top perspective view of one of the sections, and,

50 Fig. 5, is a bottom perspective view of a step section.

In the accompanying drawings, similar reference characters designate corresponding parts throughout the several views, and the letter A designates the door stoop or step as an entirety in assembled position.

The form here illustrated is provided with

four step sections designated 1, 2, 3, and 4, but it is obvious that any number of sections may be provided according to the height of the stoop or step desired. 60

Each of the step sections is formed of a hollow plastic block, and they are substantially alike in construction, varying only in size, except the top section 4, so for the sake of brevity I will only specifically describe one of the lower sections. 65

The hollow plastic block from which the section is formed is provided with side walls 5, a rear wall 6, and a front wall or riser 7; the top and bottom of the block being open 70 except at the front where an integral tread portion 8 extends across, connecting the front and adjacent side edges of the block at the top. The front portions of the side walls 5, are offset as shown at 9, while the 75 tread is provided with the usual projecting nose or flange 10, and molding 11.

The upper edges of the side walls, and rear wall of the block have longitudinally extended tongues 12, and 13, formed thereon, the inner sides of the tongues 12, of the side walls, being disposed in a single vertical plane with the inner face of the adjacent wall for a purpose to be herein set forth. In the lower edges of the side walls and rear 80 wall of the block are longitudinally extended grooves 14, and 15, which are adapted to receive the tongues of the block beneath when the sections are assembled. The lower inner edges of the sides of the blocks are 85 offset or shouldered as shown at 16, to form a firm foundation when the block is used as the base block, and consequently the grooves 14, in said lower side edges are moved off the vertical center line of the sides and will 90 receive the tongues 12, as clearly shown in Fig. 3, when the stoop is assembled. 95

The top section 4, of the stoop or steps, has the tread portion 8, entirely covering the same, as there is no necessity for further 100 tongues on the upper edge, and this section is as wide as the tread portion of the other sections. The outer sides of the lower sections, are preferably grooved at 17, to imitate stone blocks, but any desired ornamentation may be employed. 105

When assembled, as shown in Figs. 1 to 3, the various sections or plastic blocks will be disposed in superposed relation with the largest forming the base, and the rear and 110 side walls of said sections positioned in vertical alinement. The sections are held to-

gether against longitudinal or transverse creeping by the coöperatively engaged tongues and grooves, and this engagement is made additionally secure by having the 5 grooves larger than the tongues so mortar or plaster of Paris 18 can be interposed there-between to insure a snug and positive grip.

The various sections of this stoop or step are made of plastic blocks, preferably concrete, and they may be made up in stock sizes, and transported to the desired place and the stoop assembled without the employment of skilled labor. As all the block 10 sections are detachably connected it is obvious that any section may be easily replaced in event of injury, also the number of sections may be increased or diminished at will 15 to vary the size of the stoop.

I claim:

20 1. A stoop of the class described comprising a plurality of different sized superposed step sections with the largest forming the base, each section being formed of a hollow plastic block having an open top and bottom, 25 and treads across the exposed upper edges of the sections and formed integral therewith, said treads partially covering the open top of the sections.

2. A stoop of the class described comprising a plurality of different sized superposed step sections with the largest forming the base, each section being formed of a hollow block having an open top and bottom, treads 30 across the exposed upper edges of the sections integral therewith, said treads par-

tially covering the open top of the sections, and means for detachably connecting the sections.

3. A stoop of the class described comprising a plurality of different sized superposed 40 step sections with the largest forming the base, each section being formed of a hollow block having an open top and bottom, integral treads across the exposed upper edges 45 of the sections, said treads partially covering the open top of the sections, and the adjacent edges of said sections having coacting tongues and grooves to detachably lock the sections in assembled position.

4. An article of manufacture comprising 50 a plastic step formed of a hollow block having an open top and bottom, a tread portion extending across the block and connecting the front and adjacent portion of the sides at the top thereof, said tread partially covering the open top of the block, and said tread being formed integral with the block.

5. An article of manufacture comprising a plastic step formed of a hollow block having an open top and bottom, an integral 60 tread portion extending across the block and connecting the front and adjacent portion of the sides at the top thereof, said tread partially covering the open top of the block, offset shouldered portions on the lower inner 65 side edges of said block, and the top and bottom edges thereof having tongues and grooves formed thereon.

In testimony whereof I affix my signature.
SHEROD P. BARKSDALE.
